POINT-OF-PURCHASE SALES CONSOLE

Irvin M. Lemon, 321 Via Pasqual,
Redondo Beach, Calif. 90277

Filed Oct. 11, 1973, Ser. No. 405,411

Term of patent 14 years

Int. Cl. D6—04

U.S. Cl. D6—158

FIG.1

FIG.2

FIG.3

FIG.4

FIG.5

FIG.6

FIG.7

FIG.8

FIG. 1 is a front, top and left side perspective view of a point-of-purchase sales console showing my new design in non-attended condition;

FIG. 2 is a right side elevational view;

FIG. 3 is a rear elevational view;

FIG. 4 is a top plan view;

FIG. 5 is a top plan view of the console in attended condition;

FIG. 6 is a front and right side perspective view thereof;

FIG. 7 is a rear and right side perspective view thereof; and

FIG. 8 is a right side elevational view thereof.

I claim:

The ornamental design for a point-of-purchase sales console, substantially as shown and described.
